UNITED STATES PATENT OFFICE.

GEORGE PRIFOLD, OF LINWOOD, PENNSYLVANIA, ASSIGNOR TO FRANK B. FOSTER, OF HAVERFORD, PENNSYLVANIA.

BLOCK-PRINTING MACHINE.

1,145,794.

Specification of Letters Patent. Patented July 6, 1915.

Application filed May 13, 1915. Serial No. 27,824.

To all whom it may concern:

Be it known that I, GEORGE PRIFOLD, a citizen of the United States, and a resident of Linwood, county of Delaware, State of Pennsylvania, have invented certain Improvements in Block-Printing Machines, of which the following is a specification.

My invention relates to certain improvements in block printing machines for printing oil cloth, linoleum, and similar fabrics, in which the block carriers reciprocate toward and from the fabric and, when the blocks are raised, the inking mechanism inks the impression surface of the blocks and, during this interval, the fabric is moved intermittently a predetermined distance, depending upon the width of the printing surface of the blocks.

The object of my invention is to provide means for automatically engaging, holding and releasing the block carriers so that certain impressions can be made by certain blocks at given points on the fabric.

The invention is particularly adapted for printing bordered rugs in which the border extends on the four sides of the rug, necessitating the holding of certain of the blocks out of action while portions of the fabric are passing thereunder.

In the accompanying drawings:—Figure 1, is a side view of a block printing machine illustrating my invention and showing five block carriers; Fig. 2, is an enlarged side view of a portion of Fig. 1, showing the mechanism more in detail; Fig. 3, is a longitudinal sectional view on the line $a-a$, Fig. 2; Fig. 4, is an enlarged view of the broken gear and its shaft; Fig. 5, is a side view illustrating a modification of the invention; Fig. 6, is a sectional plan view of the modification; and Fig. 7, is a diagrammatic view of a rug which can be printed upon my improved machine.

Referring to the drawings, 1 is the frame of the machine having guides 2 for the vertical members 4 of the block carriers 3. The side members of the block carriers are connected by a transverse beam 5 which carries the printing blocks 6.

7 is a transverse operating shaft driven from a main longitudinal shaft 8 by worm or other gearing.

9, 9 are cams on the shaft 7 and these cams come in contact with rollers 10 on the carriers. As the cams rotate, the carriers

are raised clear of the surface of the fabric so as to allow the fabric to be moved and at the same time the reciprocating inking mechanism 11 is traversed under the block carriers to ink the printing surface of the blocks. At each side of the machine is an endless belt 12 which passes around wheels 13 and these belts engage the fabric and move it longitudinally. Mechanism is provided for intermittently moving the belts a given distance according to the width of the printing surface of the blocks.

14, 14 are latches mounted on shafts 15 and arranged to engage lugs 16 on the vertical members 4 of the carriers 3, as clearly shown in Fig. 2. The high portions 17 of the cams lift the carriers above the path of the latches 14 so as to allow the latches, which have weights 18, to move under the lugs 16, so that when the carriers are lowered by the cams their movement is stopped by the engaging latches 14. The carriers are released from the latches when the carriers are in the full elevated position; the high portion of the cams 17 being under the rollers 10 the mechanism is so timed as to withdraw the latches and hold them out of engagement until the lugs pass the latches, when an impression can be made.

On the shaft 15 is a bevel gear wheel 19 and on a longitudinal operating shaft 20 are bevel wheels 21 in which the teeth are interrupted so that, during a portion of the revolution of the shaft 20, the gears 19 are turned and during the remainder of the revolution the blank spaces of the interrupted gear 21 will pass the teeth of the gear 19, consequently, no motion will be imparted to the gears 19 or to the shaft 15. At one end of the shaft 20 is a bevel gear wheel 22, which meshes with a bevel gear 23 on a shaft 24 driven, in the present instance, from a belt or drive chain from a shaft 25 which, in turn, is driven from one of the transverse shafts 7 by belting, preferably in the form of a drive chain. These broken gears are continued throughout the length of the machine and are set so as to operate certain sets of carriers at different times.

If, for instance, a three-part rug, shown in Fig. 7, is to be printed in two colors it will take six independent printing blocks, three in each color. Two of the blocks will print the section x , two the section y and two the section z , but while the portion x

is located under the blocks they print the section y or z . These blocks must be held out of action, otherwise a misprint will result. The same is the case when the section y passes under the blocks, they print the sections x and z and, when the section z passes under the blocks, they print the sections x and y and these blocks will be held out of action. The carriers on which the blocks are mounted are controlled by the broken gears described above.

As illustrated in Fig. 4, each broken gear 21 is secured to its shaft by a set screw 26 so that it can be turned on the shaft to any position desired and locked on the shaft according to the time it is desired to hold its carrier out of action.

In some instances, as illustrated in Figs. 5 and 6, a rack 20^a may be used to engage the gears 19^a on the shaft 15^a and the broken gear 23^a may be located between the rack and the main driving shaft 24^a. The gear teeth on the rack may be made in sections and these sections may be shifted, as desired. There may be as many of these racks as desired, in the present instance I have shown three, Fig. 6. The broken gear 23^a may move the racks in one direction and coiled springs 27 may return the racks.

30 I claim:—

1. The combination in a block printing machine, of a frame; block carriers mounted on the frame; means for reciprocating the carriers to make an impression; a latch arranged to engage each carrier; an operating shaft; broken gears between the operating shaft and the latches so that certain of the latches will engage their carriers to hold said carriers out of action; and means for intermittently moving the fabric to be printed by the blocks mounted on the carriers.

2. The combination of a frame; a series

of carriers; blocks mounted on the carriers; cams for operating the carriers; a latch for each carrier arranged to hold the carrier out of position; means for intermittently moving the fabric under the carriers so that the fabric will receive an impression while it is at rest; a longitudinal shaft; broken gears on the shaft; gears on the latches engaging the broken gears; and means for driving the longitudinal shaft so that, at predetermined intervals, certain of the carriers will be held out of action by the latches.

3. The combination of a frame, a carrier mounted on the frame; a printing block mounted on the carrier; means for raising the carrier; means for intermittently feeding the fabric to be printed under the blocks; a latch arranged to engage the carrier and to hold it out of action; a gear wheel controlling the latch; a shaft; and a broken gear wheel on the shaft meshing with the gear wheel controlling the latch so that, when the timed portion of the broken gear 65 is in engagement with the gear wheel, it will turn the latch and will release the carrier.

4. The combination in a block printing machine, of a frame; a series of vertically reciprocating carriers; printing blocks on the carriers; cams for raising the carriers; means for driving the cams; means for intermittently feeding the fabric under the printing blocks; a longitudinal shaft; means for driving said shaft; a latch arranged to engage the carrier; a transverse shaft upon which the latch is mounted; a gear wheel on each transverse shaft; and a broken gear 75 adjustably mounted on the longitudinal shaft at each carrier and meshing with the gear wheel of the carrier and arranged to actuate the latches.

GEORGE PRIFOLD.
